UNITED STATES PATENT OFFICE.

THOMAS F. SOMERS, OF NEW YORK, N. Y.

CORSET.

1,256,603.

Specification of Letters Patent. Patented Feb. 19, 1918.

Application filed November 5, 1917. Serial No. 200,420.

To all whom it may concern:

Be it known that I, THOMAS F. SOMERS, a citizen of the United States, and residing at New York city, county of New York, 5 State of New York, have invented certain new and useful Improvements in Corsets, of which the following is a specification.

This invention relates to corsets and has for its object to provide an improved means 10 for adjusting the corset to fit the figure without removing it, and without time consuming lacing and unlacing.

The invention contemplates the use, with the usual two part corset, of a belt strap 15 passing around each part of the corset at the waist line and connected to the other part in the rear by a plurality of connecting straps which are guided in a novel manner, the belt straps being adapted to be tightened 20 to cause the connecting straps to draw the adjacent rear edges of the parts together until the corset fits close to the figure, and then conveniently to be tied or buckled in front.

25 The novel feature of the invention will be fully disclosed in the following description, taken in connection with the accompanying drawings, in which:—

Figure 1 is a view of the entire corset 30 spread out flat;

Fig. 2 is a perspective view of the corset as it appears when being worn; and

Fig. 3 is an enlarged view of a small portion of the back.

35 My improved adjusting means may be used with corsets of different styles and is not limited to use with the particular kind of corset shown in the drawings, in which only a small portion extends above the waist 40 line, provided that the corset is in sections or has an expansion slit therein to which the invention may be applied.

The sections 10 and 11 of the corset shown 45 are similar in shape and are provided with the usual fastening devices 12 for securing the front edges 13, 14 together. The rear edges are held together by my improved adjusting means which comprises the belt straps 15, disposed along the waist line of 50 the garment and held in place by the tape guides 16, and the connecting straps or tapes 17 which are each secured at one end to the belt strap 15 of one of the parts and at the other end to the edge of the other section 55 of the corset.

Each of the sections is provided with a

series of aligned slots 18 which serve as guides for the connecting tapes secured to the other section. These guides are important, as they prevent the sections of the corset from becoming separated when the corset is not in use, and also have the more important function of directing the connecting tapes so that they exert a pull on the edge of one section which tends to draw it directly toward the other section instead of allowing it to exert a diagonal pull toward the belt strap, as would be the case if the guides were not present. The slots in each part or section are of course directly opposite the points at which the connecting straps passing therethrough are fastened to the other part.

In putting on the corset the belt straps are loose, so that the rear edges may separate while the front edges are fastened together. The free ends of the belt straps being then in front of the body, may be grasped by the hands and pulled forward to tighten the connecting straps and draw the rear edges together. When the corset fits the body tightly the ends of the belt straps are tied together in front.

Having thus described the invention, what is claimed as new and desired to be secured by Letters Patent is:—

1. In a corset, the combination with two similar parts or sections, adapted to be fastened together at their opposite edges, of positive fastening devices for the front edges of the parts, and adjustable means connecting the rear edges thereof so as to permit the relative adjustment of the parts to conform to different figures, said adjustable means comprising a belt strap disposed along the waist line of each part, a plurality of connecting straps each secured at one end to the back edge of one part and having its other end secured to the belt strap of the opposite part, and a guide on each of said parts for each individual connecting strap secured to the other part, said belt straps being adapted to be tightened to draw the rear edges of the parts together and to be fastened together in front of the corset, each connecting strap being directed by its corresponding guide to exert a pull on one section which tends to draw it directly toward the other section.

2. In a corset, the combination with two similar parts or sections adapted to be fastened together at their front and rear edges,

each of said parts having a series of aligned slots adjacent and parallel to its rear edge, of positive fastening devices for the front edges of the parts and adjustable means connecting the rear edges thereof so as to permit the relative adjustment of the parts to conform to different figures, said adjustable means comprising a plurality of connecting straps each secured at one end to one part or section adjacent its rear edge and extending through one of the slots of the other part and guided thereby, and a belt strap ar-

ranged along the waist line of each part and connected to the connecting straps secured to the other part, said belt straps being adapted to be tightened to draw the rear edges of the parts together and to be fastened together in front of the corset, each connecting strap being directed by its corresponding guide to exert a pull on one section which tends to draw it directly toward the other section.

In testimony whereof I affix my signature.
THOMAS F. SOMERS.
